UNITED STATES PATENT OFFICE.

AUGUST F. HUTZEL, OF ANN ARBOR, MICHIGAN.

BRACKET FOR CLOTH RADIATOR COVERS.

Application filed January 6, 1923. Serial No. 611,074.

To all whom it may concern:

Be it known that I, AUGUST F. HUTZEL, a citizen of the United States, residing at Ann Arbor, in the county of Washtenaw and State of Michigan, have invented new and useful Improvements in Brackets for Cloth Radiator Covers, of which the following is a specification.

This invention relates to covers for the radiators of heating systems, and more particularly to brackets for supporting cloth covers thereon.

The primary object of this invention resides in the provision of means for supporting cloth covers, over the radiators of heating systems, so they will be retained in taut condition out of contact with the coils of the radiators.

Another object of this invention resides in the provision of means for supporting double cloth covers in taut condition over a predetermined area of the coils of radiators for heating systems.

A further object of this invention resides in the provision of a certain combination of coacting elements adapted to be contracted for receiving a cloth cover, for a heat radiator, prior to being released to retain the cover in taut condition over the radiator.

A still further object of this invention resides in the provision of particularly formed brackets which are capable of rigidly supporting cloth covers, over heat radiators, so they can be readily removed without displacing the bracket.

With these and other objects in view, this invention resides in certain novel features of construction, arrangement of parts and combination of elements to be hereinafter more particularly set forth in the specification, illustrated in the accompanying drawings and pointed out in the appended claims.

In the accompanying drawings:

Fig. 1 is a front view of a portion of a heat radiator showing a double cloth cover in operative position thereover.

Fig. 2 is a front view of a portion of a heat radiator showing the elements of this invention secured in operative position on the radiator with the cloth cover removed.

Fig. 3 is a side view of the elements of this invention as disposed in Fig. 1.

Fig. 4 is a detail perspective view of a

portion of one of the brackets showing one of the spring clips thereon.

Fig. 5 is a longitudinal sectional view of one of the guide blocks for the brackets.

Fig. 6 is a detail view of a portion of 60 a radiator showing one of the supporting brackets contracted for receiving the cloth cover.

Fig. 7 is a detail perspective view of one of the supporting brackets per se. 65

Fig. 8 is a detail perspective view partly in section of one form of cloth cover employed in conjunction with the elements of this invention.

Fig. 9 is a detail perspective view of one 70 of the guide blocks.

Fig. 10 is a perspective view of one of the U-shaped yokes.

In the present embodiment of this invention, the letter R designates a conventional 75 illustration of a radiator of heating systems.

Suitably secured to the radiator R as at 5 are guide blocks 6 which are provided with spaced ears 7 having apertures 8 therein for slidably retaining the supporting brackets to be hereinafter set forth. While the aforesaid guide blocks 6 may be rigidly secured to the radiators in any suitable manner, the present disclosure employs 80 U-shaped yokes 9 adapted to straddle the connecting tubes T of the radiators with their free ends extending through apertured lugs 11 on the guide blocks for receiving nuts or thumb-screws 12. In order 90 to prevent the blocks from moving, after the nuts or thumb-screws have been tightened, the under sides of the blocks are provided with serrations 13 for engagement with the contacting portions of the radiators. 95

Each cloth supporting bracket is preferably formed from a single piece of heavy wire bent upon itself as at 14 and extended in parallelism as indicated at 15, whereupon the cloth receiving arm 16 thereof is arched a convenient distance above and beyond the supporting arm 17 thereof. The supporting arm 17 of each bracket is bent substantially at right angles to the arched portion thereof and is provided with apertures 19 and 20, for purposes to be hereinafter set forth. 105

Each bracket is supported by its companion guide block through the instrumentality of the ears 7 and its arm 17, and is re- 110

tained in laterally yieldable relation with the supporting block thereof through the provision of an expansible coil spring 18 adapted to bear against one of the ears 7 and a washer 20' which bears against a stop pin 21 passing through the aperture 19 in the arm 17.

In order to steady the looped end of each bracket and secure the rigidity of said portion 10 a frictional leaf spring 22 is attached to one of the parallel branches of the bracket and extended in contact with one of the coils of the radiator, whereupon the looped end of each bracket will be yieldably retained 15 between the radiator and the wall W of the building.

While fabric covers of various types may be conveniently employed in conjunction with the particular brackets herein set forth, 20 the present disclosure employs what is termed a double cover type, the same being designated 23. This particular type of cover consists of a sheet of fabric having three of its edges secured or stitched and 25 one edge open so that the same can be slipped over the supporting portions 17 of the brackets.

To facilitate placing the cover over the brackets, the distance between the supporting portions thereof is shortened by compressing the coil springs until the apertures 20 are exposed beyond the outer sides of the ears 7 whereupon pins are inserted therein to retain the brackets in contracted condition. After the cover has been properly assembled, the pins are removed, whereupon 35 the brackets will be ejected laterally in opposite directions by the springs until checked by the bound sides of the cover, thus resulting in the cover being stretched.

With this invention fully set forth, it is manifest that means have been provided for readily supporting cloth covers over heat radiators so that the supports at both ends

may be contracted for assembling the cloth 45 on the brackets, but it is to be understood that the right is reserved to employ one stationary bracket and one yieldable bracket instead of similar brackets as herein disclosed. 50

Having thus described this invention what I claim and desire to protect by Letters Patent is:—

1. The combination with a heat radiator, 55 of a pliable cloth cover, stationary guide blocks secured to the radiator, cover supporting brackets slidably supported by the stationary guide blocks, yieldable means between the guide blocks and supporting brackets for stretching the cloth cover and 60 frictional clips carried by the brackets remote from the yieldable means therefor.

2. The combination with a heat radiator, 65 of a pliable double cloth cover, guide blocks in spaced relation on the radiator, a yoke binding each guide block to the radiator, brackets slidably engaged by the guide blocks and supporting the cover, and means for yieldingly supporting the brackets on the guide blocks. 70

3. The combination with a heat radiator of guide blocks secured in spaced relation thereon, apertured ears on said guide blocks, securing means between the radiator and guide blocks, brackets having supporting 75 arms slidably engaged by the ears of the guide blocks, washers fixed on the slideable arms of the brackets and disposed between the ears of the guide blocks, expansion coil springs on the supporting arms of the 80 brackets between the washers and certain of the ears on the guide blocks, and frictional clips carried by the brackets in contact with the radiator.

In testimony whereof I affix my signature. 85

AUGUST F. HUTZEL.
